UNITED STATES PATENT OFFICE.

FRANKLIN F. WILLIAMS, OF ST. LOUIS, MISSOURI.

SHOE HEEL.

1,404,822.

Specification of Letters Patent. Patented Jan. 31, 1922.

Application filed September 2, 1919. Serial No. 321,074.

To all whom it may concern:

Be it known that I, FRANKLIN F. WILLIAMS, a citizen of the United States, residing at St. Louis, Missouri, have invented a 5 certain new and useful Improvement in Shoe Heels, of which the following is a full, clear, and exact description, such as will enable others skilled in the art to which it appertains to make and use the same, reference being had to the accompanying drawings, 10 forming part of this specification.

My invention relates to an anti-slipping, wear-resisting, cushioning device or attachment that is designed for use upon the heels 15 of footwear and also upon the lower ends of the legs of chairs, tables, desks, pianos, and like furniture.

The principal objects of my invention are, to provide a relatively simple and inexpensive disk that is capable of being readily applied to or removed from a heel of a shoe or the leg of a table or other piece of furniture, the main body portion of which device 20 is preferably formed of a rubber composition material, the nature of which tends to resist wear and eliminate slipping when in contact with smooth surfaces, and said material being elastic or yielding to a certain degree, thereby tending to cushion or break the force 25 of impact between the device and a solid surface upon which the device is placed.

A further object of my invention is to provide a cushioning and wear-resisting disk which, when placed on the heel of a shoe or 30 the like, can be loosely attached to said heel, in order that said device will rotate while in service, thereby equalizing the wear on the underface of the device, with the result that the heel portion of the shoe will at all times 35 be maintained in proper position and without tending to "run over" and lose its shape, there being a concentrically corrugated metal plate with its marginal edges embedded in the disk, said plate having a central opening 40 for the passage of a fastening screw.

With the foregoing and other objects in view my invention consists in certain novel features of construction and arrangement of parts, hereinafter more fully described and 45 claimed, and illustrated in the accompanying drawings, in which—

Figure 1 is an elevational view of a shoe with my improved cushioning and wear-resisting disk applied to the underside of the 50 heel thereof.

Figure 2 is a detail sectional view taken

through the lower portion of a heel to which my improved disk is applied.

Figure 3 is a plan view of the reinforcing plate that is partially embedded in the body 60 of the disk.

Figure 4 is a vertical sectional view taken approximately on the line 5—5 of Figure 3.

Referring by numerals to the accompanying drawings, 10 designates the body of the 65 disk, which body is preferably of any desired diameter and thickness, although where the device is intended for use upon shoe heels, I have demonstrated that said disk should have a thickness of approximately one-quarter to three-eighths of an 70 inch. This disk is preferably formed of rubber or a composition having rubber as its principal ingredient, thus providing a body having a certain degree of elasticity to give 75 a cushioning effect while in service, and at the same time providing a construction that will minimize the tendency to slip on smooth surfaces.

Embedded in this body 10 is a plate 11, 80 preferably formed of thin flat metal, the diameter of which is less than the diameter of the body 10.

Formed in the plate preferably at points halfway between its center and periphery 85 are apertures 12 which are filled with the material of which the body 10 is formed, thus firmly anchoring the disk 11 in said body.

A recess 13 of any desired shape is formed 90 in the lower central portion of body 10, thus exposing the underface of the central portion of plate 11 and passing through an opening in the center of said plate 11 and into the central portion of the upper part of the body 10 is a fastening device, preferably 95 a screw 14, the threaded shank of which is seated in the body of the heel or in the lower portion of the leg of the piece of furniture to which the device is attached. 100

In the event that the device is used on the legs of furniture or the like, the recess 13 performs the functions of a suction cup to cause the device to firmly adhere to the floor, and to enhance this effect the underside of 105 the body 10 may be provided with a plurality of small recesses as shown by the dotted lines *a*, in Figure 3.

If desired, the attaching screw 14 may be seated in the heel so as to permit the device 110 to rotate freely in all directions, such rotation being effected by the frictional contact

between the underface of the device and the surface of the floor or ground, and as a result of this automatic rotation of said device, the wear upon its undersurface is equally distributed.

If desired, the screw can be tightened to firmly secure the disk to the heel, and as the rear of side of the undersurface of said disk becomes worn, said disk can be adjusted from time to time by loosening the screw, and turning the disk partially around to bring a fresh wearing surface toward the rear or side of the heel, after which the screw is tightened.

15 The metal plate is provided with concentrically arranged ribs or corrugations 15 to give it strength and also prevent slippage or creepage of the rubber disk relative thereto,

which might, as in the instance of a flat plate with perforations therein, tend to cut or shear the anchorages passing through the perforations.

I claim:

A shoe heel comprising a yielding body portion formed with a recess in its lower 25 face, a concentrically corrugated metal plate having its marginal edges embedded within said body portion and on a plane with the inner wall of said recess, said marginal edges having perforations filled with the 30 material of the body portion, and said body portion conforming to the shape of said marginal concentric corrugations.

In testimony whereof I hereunto affix my signature this 28th day of August, 1919.

FRANKLIN F. WILLIAMS
